UNITED STATES PATENT OFFICE.

AMOS CALLESON, OF BROOKLYN, NEW YORK.

BOTTLE-HEIGHT-COMPENSATING MECHANISM.

Original application filed June 25, 1923, Serial No. 647,468. Divided and this application filed June 7, 1924. Serial No. 718,467.

The present application constitutes a division of my application for patent for bottle filling and sealing machine filed June 25, 1923, Serial No. 647,468, and the invention 5 herein set forth consists in an improved means for compensating for bottles or other containers whose height actually exceeds a given height-standard, so that the top of each bottle will be at a given level when 10 some other operation, as sealing the same, is later performed thereon.

In the drawings,

Fig. 1 is a side elevation, partly in section, of a bottle sealing and filling machine 15 embodying the improved compensating mechanism;

Fig. 2 shows in front elevation the turret *d* of the machine, the cam *c* (the turret being broken away to reveal the cam), and a part 20 of one of the container supporting means;

Fig. 3 shows in plan, partly in section, what appears in Fig. 2; and

Fig. 4 is a sectional view of said turret, said cam and container supporting means in 25 a plane radial with respect to the cam.

A supporting structure is afforded by a cylindrical base *a* and a vertical non-rotative shaft *b* upstanding therefrom; said structure includes a fixed cam *c* having a peripheral cam-groove *c'* and a hump *c''*. A rotary structure is journaled on the supporting structure and rotative around the shaft *b* and its cam and includes a turret *d* and above the turret any suitable abutment *e* (as 30 the sealing head part of the machine illustrated) for the bottles or other containers *f*. It is not material by what means the structure *d*—*e* is rotated; nor, in fact, which structure rotates relatively to the other. 35 The machine shown is adapted to receive a plurality of bottles at a time and hence there are shown a plurality of abutments but only one of these and the set of parts coactive therewith in compensating are material and will be described.

Housed by the base *a* and movable in a vertical slot *d'* (Fig. 3) of the turret is a carrier *g* having a roller *g'* which runs in the peripheral groove *c'* of the cam *c*. This 40 carrier is penetrated by the squared portion of a stem or spindle *h* adapted to slide vertically in the carrier and having a depending trunnion *h'* guided in a bearing *d''* at the lower end of the turret *d* and an up- 45 standing trunnion *h''* pinned or otherwise

fixed in the depending tubular stud *i'* of a bottle rest *i* which may be guided in a bearing *d''* in the upper portion of the turret and has a bottle pad or cushion *i''*. Any means well known in the art is employed to frictionally resist the movement of the plunger formed by the bottle rest and its stem *h* relatively to the carrier *g*; in Figure 3 this is shown as a pair of friction plates *j* held 50 bearing against opposite sides of the squared part of the stem by springs *k* interposed between the friction plates and set screws *l*. In a vertical central slot *m* of the squared part of the stem is fixed by a pin *n* (Fig. 4) a block *o* having an underneath downwardly 55 and inclined stepped surface *o'*. The carrier also has a vertical and central slot *p* on the floor or lower end surface of which slides a block *q* having an upper and downwardly inclined stepped surface *q'* to engage 60 the surface *o'* of the block *o*; the block and the space receiving it and formed between surface *o'* and the floor of slot *p* being 65 tapered (in the present example both are tapered but it is not essential that both 70 should be), the block constitutes in effect a wedge-chock and I so term it herein. A spring *r*, coiled about a pin *s* which projects from a plate *g''* which covers the carrier slot *p* and is suitably affixed to the outer face 75 of the carrier, normally holds the block *q* inwardly (Figs. 1 and 4). At a suitable point in each revolution of the rotary structure the block *q* is shifted radially outwardly so that, being clear of the block *o*, 80 the bottle supporting plunger *h* can be depressed in the carrier subject to the resistance of its friction grip means already described. This is accomplished by the hump 85 or projection *c''* of the cam *c* encountering 90 the inwardly projecting heel *q'* of the block *q*.

The compensating is effected as follows: When, as by the rise in the cam-groove *c'* shown at the left in Fig. 2, a movement as 95 between the container supporting means *g* and *h*—*i* and the abutment means *e*, one toward the other, occurs, so that the head of a container *f* supported on the plunger or 100 container supporting member *h*—*i* and the abutment means impinge against each other, the plunger will yield downwardly in the carrier if the block *q* is not present to prevent such yielding, and in the present adaptation (where the block is normally present 105 110

under the plunger) said block will be displaced from under the plunger to allow such yielding at the proper time by the hump c^2 of the cam as it sweeps around. When the 5 yielding to the full requirement of the container height is completed the block is established under the plunger to thereby prevent further yielding, in the present case effected by spring r , the hump c^2 having 10 meantime cleared the block.

The invention is further not concerned with any particular purpose in obtaining positive resistance to yield of the supporting member in the carrier after such yield 15 has proceeded to the extent determined by the height of the container. But assuming that it is for proper support of the container in the act of sealing the same, as by the sealing head e , it will be understood 20 that following the movement, one toward the other, as between the abutment means and container-supporting means g and $h-i$, there will be further movement, and in the present example this is effected as follows: 25 After the movement for compensating is effected by the rise in cam-groove c' shown at the left in Fig. 2 the peripheral cam-groove t' in a cam t fixed on shaft b depresses the abutment means until the rise in 30 the cam-groove c' at the right in said figure can effect a second movement by elevating the container supporting means, the abutment means being for this purpose suitably guided vertically in an extension d^{10} 35 of the turret d and having a roller e' travelling in cam-groove t' .

Between the two mentioned rises of the cam-groove c' said groove is appreciably depressed, as shown in Fig. 2 at the near side 40 of the cam c . When the roller g' enters this part of the groove it restores the carrier to its starting position or lowest limit and the head i of the plunger $h-i$ impinging the bearing d^3 said plunger assumes 45 its original elevation in the carrier. Thereupon the block g will assume its normal position (Fig. 4) if (the bottle being of proper height) it does not already occupy that position because the necessity for compensation 50 did not arise.

Having thus fully described my invention, what I claim as new and desire to secure by Letters Patent is:

1. The combination, with coacting means 55 for exerting pressure on a container interposed between them, one of such means being adapted to undergo movement toward the other to a definite limit and one including a carrier and a container-thrust-assuming 60 plunger arranged to yield in the carrier from the other of said means a distance determined by the height of the container when interposed between them on such movement, of means to move the movable 65 one of said coacting means to said limit, said

coactive and last-named means being arranged to rotate one relatively to the other around an axis substantially parallel with the path of such yielding to cause such movement, and a chock movable crosswise 70 of and into said path and into chocking relation to said plunger and carrier and having its movement controlled by the last-named means.

2. The combination, with coacting means 75 for exerting pressure on a container interposed between them, one of such means being movable toward the other to a definite limit and one including a carrier and a container-thrust-assuming plunger arranged to yield in the carrier from the other of said means a distance determined by the height of the container, of means to move the movable 80 one of said coacting means to said limit and simultaneously cause such yielding, and a chock normally urged to move crosswise 85 of the path of such yielding and into interposed chocking relation to said plunger and carrier, the last-named means opposing such movement of the chock until the movable 90 means has been moved to said limit and thereupon freeing the chock.

3. The combination, with coacting means 95 for exerting pressure on a container interposed between them, one of such means being adapted to undergo movement toward the other to a definite limit and one including a carrier and a container-thrust-assuming plunger arranged to yield in the carrier from the other of said means a distance determined by the height of the container 100 when interposed between them on such movement, of means to move the movable one of said coacting means to said limit, said coactive and last-named means being arranged to rotate one relatively to the other around an axis substantially parallel with the path of such yielding to cause such movement, a chock movable crosswise of and into said path and into chocking relation to 105 said plunger and carrier, and means to move said chock into said relation when the movable means has been moved to said limit.

4. The combination, with coacting means 110 for exerting pressure on a container interposed between them, one of such means being movable toward the other to a definite limit and one including a carrier and a container-thrust-assuming plunger arranged to yield in the carrier from the other of said means a distance determined by the height of the container, of means to move the movable 115 one of said coacting means of said limit and simultaneously cause such yielding, and a chock normally held in interposed chocking 120 relation between said plunger and carrier and movable crosswise of the path of such yielding out of said relation, the last-named means being adapted to move said 125 chock out of said relation and hold it out 130

of the same until movement of the movable means to said limit has been effected and thereupon free the chock.

5. The combination, with coacting means for exerting pressure on a container interposed between them, one of such means being movable toward the other to a definite limit and one including a carrier member and a container-thrust-assuming plunger member arranged to yield in the carrier member from the other of said means a distance determined by the height of the con-

tainer, of means to move the movable one of said coacting means to said limit and simultaneously cause such yielding, and a 15 chock movable crosswise of the path of such yielding and into interposed relation to said plunger and carrier member to limit the yielding, one of the surfaces of the two pairs of the contacting surfaces afforded 20 by said members and chock being oblique to said path and also stepped.

In testimony whereof I affix my signature.

AMOS CALLESON.
